(57) CLAIM

The ornamental design for a chest, as shown and described.

DESCRIPTION

FIG. 1 is an upper perspective view of a chest showing my new design.

FIG. 2 is front view thereof;

FIG. 3 is a rear view thereof;

FIG. 4 is a side view thereof;

FIG. 5 is an opposite side view thereof; and,

FIG. 6 is a top plan view thereof.

The woodgrain pattern on the chest forms part of the claimed design. The broken lines shown in FIGS. 2-5 illustrate portions of the chest that form no part of the claimed design.

1 Claim, 3 Drawing Sheets
